STAPLE FEED MECHANISM FOR STAPLING MACHINES

Nathaniel M. Olney, New York, N. Y., assignor to
Speed Products Co., Inc., Long Island City,
N. Y., a corporation

Application June 4, 1946, Serial No. 674,326

2 Claims. (Cl. 1—3)

1

This invention is directed to stapling machines and specifically deals with an improved and serviceable staple propelling device or follower in a stapling machine wherein a magazine appropriately sustains a strip of wire staples and wherein self retracting manually controlled slidably guided plunger means is utilized to sever and drive the foremost staple from the stack through suitable sheet material to be fastened. The dominant object of the invention resides in the provision of a novel staple pusher or follower within and shiftable longitudinally of the staple magazine and having spaced and posterior bearings fixedly retaining a fulcrum pin or stay for desirably maintaining one end of a coiled spring having another end connected to the cover for the magazine. Another important object is realized in the provision of means to permit quick assembly of one end of the coiled spring with the staple propelling device or follower. A further object is to provide a simplified follower having spaced bearings for straddling a terminal coil of the helicoidal spring and for retaining an appropriate pin threaded through the spaced bearings and the terminal coil. Another object is concerned with rotatably sustaining the terminal coil on the stay or fulcrum pin. Other important aspects, advantages and functional and structural features of the invention will appear from the following detailed specification considered in the light of the accompanying drawings wherein:

Fig. 1 is a longitudinal and vertical sectional view of a stapling machine showing the slidably guided staple follower according to my invention.

Fig. 2 is a horizontal sectional view on the line 2—2 of Fig. 1.

Fig. 3 is a transverse sectional view on the line 3—3 of Fig. 1.

Fig. 4 is a fragmentary perspective view of Fig. 1, however illustrating the swingable cover in a partially opened position relative to the staple carrying magazine.

Fig. 5 is a perspective view of the follower, and

Fig. 6 is a perspective view of the slotted staple supporting rail.

The stapling machine generally designated S is characterized by the magazine M appropriately carrying the fixed rail R on which a strip of wire staples W are slidably guided. The wire staple strip is of the conventional inverted U-shaped form and foremost staple as 10 is adapted to be ejected through a vertical staple

2

guideway or gap 11 between the front wall 12 of the cover C and front face 13 of the rail by a vertically slidably guided blade 14 of the spring controlled vertically and slidably guided driver D having attached thereto the manipulatable head 15. Attached to the driver and cover is a normally contracted but extendible helicoidal spring 16 for normally holding the driver elevated.

10. The cover C is pivotally mounted on the fulcrum pin P carried by the magazine M. Also pivoted on the cover are the spaced upstanding lugs 17 projecting from the base B carrying the anvil A which is provided with suitable clinching indent 18.

Slidably guided by the cover is the latch L having the manipulatable wings 19 extending laterally of the cover C.

Trained about the slidably guided latch L is 20. the helicoidal spring 21 having one end fastened to a lug 22 extending from the cover C.

A pivoted clearing latch 23 is yieldingly sustained on the free end of the leaf spring 24 having its anterior end secured by a rivet 25 to the base B. The clearing latch is adapted to removably project into opening 26 to removably interlock with the bottom wall of the magazine.

The slidably guided latch L removably interlocks with the walls of the transversely aligned notches 27 in the spaced wings 28 projecting upwardly from the sides of the magazine M.

The foregoing structure is more particularly set out in United States Letters Patent 2,311,643, issued to Stephen A. Crosby February 23, 1943.

35. According to the invention an inverted U-shaped staple propelling device or follower F is slidably mounted on the fixed rail or support R. Specifically the follower has its depending sides 30 slidably arranged in the longitudinally disposed and spaced staple guide channels 31 formed by the sides of the cover and the sides of the magazine.

Anchored to the top wall 32 of the staple follower or pusher F is the rivet 33 having an enlarged cylindrical portion 34 slidably guided in the elongated longitudinally disposed rectilinear slot 35 in the top wall 36 of the rail.

Cooperating with the underface of the top wall 36 is a relatively enlarged head or flange 37 to preclude involuntary separation of the follower from the rail.

The posterior end of the slidably guided staple follower is provided with the transversely aligned spaced ears or bearings 38 adapted to straddle terminal coil or eye 39 of the helicoidal spring

21. It will be observed that the terminal coil 39 is bent substantially normal to the body of the spring 21.

A cylindrical fulcrum pin or stay 40 is threaded through the bores of the transversely aligned bearings 38 and through the opening in the terminal coil 39. This fulcrum pin has its ends appropriately fixedly anchored to the ends of the bearings 38 to preclude dislodgement thereof. By the arrangement disclosed, the terminal coil is rotatably sustained by the fulcrum pin and has adequate play to shift therealong in the matter of opening or closing of the magazine by the swingable cover.

On pivotally opening of the cover the lower leg 41 of spring 21 retracts the follower towards the rear of the magazine to permit mounting of a staple strip on rail R. On closing of the cover leg 41 urges the follower forwardly consequently driving the staple strip forwardly to present the foremost staple under the raised staple ejecting blade 14 of the driver D which if depressed causes the blade 14 to shift the foremost staple through the vertical guideways 11, through the sheet material (not shown) to be fastened and against the indentations 18 of the anvil for clinching the ejected staple in a manner well understood.

Of course when the driver D is depressed spring 16 is elongated and upon removal of manual pressure on the head 15 the driver automatically retracts to position its blade 14 above the rail as indicated in Fig. 1 awaiting to again sever a foremost staple of the staple strip.

Various changes may be made in the details of construction and arrangement of parts without departing from the spirit of the invention or sacrificing any of the advantages thereof inherent therein.

I claim:

1. In combination, a staple magazine having a rail including a longitudinally disposed slot, a staple follower comprising a top wall and spaced

depending sides straddling said rail, pin means secured to and depending from said wall and having a portion slidably guided by the walls of said slot, means carried by said pin means and coacting with said rail to preclude separation of said follower from said rail, spaced and hollow bearing means extending from said follower, a helicoidal spring having a terminal coil interposed between said bearing means, and stay means carried by said bearing means and threaded through and rotatably surrounded by said terminal coil.

2. In combination, a staple magazine having a rail including a longitudinally disposed slot, a staple follower comprising a top wall and spaced depending sides movably straddling said rail, pin means secured to and depending from said wall and having a portion slidably guided by the walls of said slot, a head carried by said pin means and coacting with said rail to preclude separation of said follower from said rail, spaced and hollow bearing means integral with and extending from the posterior portion of the wall of said follower, a helicoidal spring having a terminal coil interposed between said bearing means, and fulcrum stay means carried by said bearing means and threaded through and rotatably surrounded by said terminal coil.

NATHANIEL M. OLNEY.
